UNITED STATES PATENT OFFICE.

VETAL BÉSSIER, OF NEW YORK, N. Y., ASSIGNOR TO HIMSELF AND JOHN AMMON, OF SAME PLACE.

PIANISSIMO-STOP FOR PIANO-FORTES.

SPECIFICATION forming part of Letters Patent No. 337,552, dated March 9, 1886.

Application filed December 3, 1884. Serial No. 149,386. (No model.)

To all whom it may concern:

Be it known that I, VETAL BÉSSIER, of the city, county, and State of New York, have invented a new and Improved Pianissimo-
5 Stop for Piano-Fortes, of which the following is a full, clear, and exact description.

The object of my invention is to provide a new and improved pianissimo-stop for piano-fortes of all kinds, whereby the tones can be
10 subdued as much as may be desired, or rendered inaudible altogether.

The invention consists in a piano provided with a damper-rail between the sounding-board and the strings, in addition to the usual
15 damper devices.

Reference is to be had to the accompanying drawings, forming part of this specification, in which similar letters of reference indicate corresponding parts in all the figures.

20 Figure 1 is a face view of an upright piano provided with my improved stop, the front plate being removed. Fig. 2 is a cross-sectional elevation of the same, the pianissimo-stop being out of use. Fig. 3 is another sec-
25 tional view, the pianissimo-stop being in use.

A rail, A, is placed between the strings B and the sounding-board C, and has the side facing the strings covered with felt, soft leather, or cloth, felt being preferred. The
30 said rail is arranged to be moved toward and brought in contact with the strings, and it may be arranged to swing or to slide toward the strings and at the same time slide parallel with the strings a greater or less dis-
35 tance.

In the construction shown bars D project downward from the ends of the rail, and through apertures in the said bars the ends
40 of angle-levers E pass, which are pivoted on the inner surfaces of the end pieces, the other ends projecting upward. Sliding rods F are arranged in the end blocks, G, and have but-
45 tons or knobs H on their outer ends, the inner ends being connected with the angle-levers E. Rods J, secured to the lower ends of the bars D, pass through boards K, and thus guide the said bars D. The back of the rail A rests against the lower smaller ends of wedges L, secured on the inner surface of the
50 sounding-board, above the top of the rail, and on the front surfaces of the bars D wedges N are secured, which rest against pins O, pro-
jecting from the inner surface of the ends of the casing.

The piano is provided with the usual damp- 55 ers, stops, and the piano and forte pedals, which are not shown.

The operation is as follows: By pulling out the rods F the angle-levers E are turned on their pivots and move the bars D upward, 60 whereby the rail A is moved upward and at the same time is forced against the strings B by the wedges L. If a string is now struck by a hammer, the rapidity of the vibrations will be reduced to such an extent that the 65 tone is inaudible. By pushing back the rods F the rail A is lowered and pushed from the strings by the pins O, against which the wedges N work.

By means of my improved stop the instrument can be so adjusted that the tones will 70 not be heard, and the player cannot disturb others while practicing. If the player wishes to hear the tones, the rail A can be so adjusted by raising it less than to the full height that 75 the tones are softened considerably and can only be heard by the player.

The stop can be applied on grand, square, or upright pianos.

Having thus described my invention, what 80 I claim as new, and desire to secure by Letters Patent, is—

1. A piano provided with a sound-deadening rail having its entire outer surface cov- 85 ered with felt, leather, or other fabrie, which rail is located between the strings and the sounding-board, and is mounted to move to and from the strings, substantially as herein shown and described.

2. In a piano, the combination, with the 90 case, strings, sounding-board, and hammer mechanism, of a sound-deadening rail between the sounding-board and strings, and of wedges secured on the sounding-board for pressing the damper-rail against the strings, substan- 95 tially as herein shown and described.

3. In a piano, the combination, with the case, the strings, sounding-board, and hammer mechanism, of the wedges L on the sounding- 100 board, the wedges N on bars connected with the rail, and of the pins O, projecting from the inner surface of the end pieces of the box, substantially as herein shown and described.

VETAL BÉSSIER.
